UNITED STATES PATENT OFFICE.

ALONZO S. WILLIAMS, OF TAFT, OKLAHOMA.

HEADLIGHT-ADJUSTER.

1,012,954.

Specification of Letters Patent. Patented Dec. 26, 1911.

Application filed July 22, 1911. Serial No. 639,904.

To all whom it may concern:

Be it known that I, ALONZO S. WILLIAMS, a citizen of the United States, residing at Taft, in the county of Muskogee and State 5 of Oklahoma, have invented new and useful Improvements in Headlight-Adjusters, of which the following is a specification.

The general object of the invention is to enable the operator of a traction device, 10 such as a locomotive, to reflect the light on the track or to one side thereof as when the locomotive is rounding a curve.

Other objects will appear and be better understood from the following description 15 taken in connection with the accompanying drawings, in which,

Figure 1 is a diagrammatic view of the invention. Fig. 2 is a vertical cross section taken through the table support and lower 20 portion of the headlight. Fig. 3 is a detail longitudinal section of one of the cylinders. Fig. 4 is a detail front elevation of one of the cylinder supports. Fig. 5 is a detail sectional plan of the valve. Fig. 6 is a detail 25 section of the headlight and table also showing the locking connection between the parts.

The headlight 5 is supported for rotation on a disk 6 adapted to be connected in any 30 preferred manner with the headlight 5 such as by pins 7 which enter openings in the base of the headlight. The disk 6 is let into a depression 8 in the upper face of the rigid table 9 which may be connected in any preferred manner to the locomotive or car as the case may be so as to be supported horizontally. The shaft 11 carried by the disk 6 has a bearing in the table 9 and carries a toothed wheel 12 which is oscillated by the 35 rack portions 13 of the piston rods 14 extending through cylinders 15 which, when the device is applied to the locomotive, are arranged on the opposite sides of the boiler thereof. The cylinders 15 extend 40 through U-shaped extensions 16 in brackets 17 which, when the device is employed with a locomotive, are arranged on opposite sides of the boiler thereof and for adjustably securing the cylinders to the brackets or "truing" them whenever required to insure proper sliding of the rods 14, I may employ any preferred means such as set screws 18 screwed into the opposite sides of the extensions 16 and engaging with the cylinders 15. The pistons 19 are normally

at the intermediate portions of the cylinders 15 and yieldingly held by thrust springs 20.

Any motive fluid such as air may be used for reciprocating the pistons and, in the present instance a line made up of two conducting pipes 21 and 22 connected at one end to the casing 23 of a two-way valve 24, the handle of which is designated at 25. Each conducting pipe is connected to the cylinders 15 by extensions 26 and 27 which 65 connect with opposite end portions of the cylinders or beyond the opposite ends of the pistons 19. A locking connection between the headlight 5 and the table 9 may be effected in any preferred manner such as by 70 tapered rolls 28 extending upwardly into curved guide slots 29 in the table and rotating on threaded pins 30 screwed into the base of the headlight 5.

When it is desired to turn the headlight 75 in one direction the handle 25 is turned so as to admit fluid to one of the pipes such as the pipe 21. This will have the effect of moving the pistons and their rods relatively to each other and compressing one of the 80 springs 20. When the headlight has been turned for the required distance the valve is moved to lap, in which event the headlight will be held in adjusted position. When the handle is moved to release, the 85 air flows through the cylinders to the pipe 21 and through the exhaust 31 in the casing 23. The headlight then is turned to its normal position by the action of the compressed spring. It may here be stated that 90 either spring will be sufficiently powerful to restore the parts to their normal positions but the springs will be unable one to compress the other. The forward end portions of the rods 14 have bearings in hangers 95 32 depending from the table 9. Owing to the fact that the motive fluid acts on both pistons the headlight 5 will be turned without jerk or intermittent movements. Vibration of the headlight will also be prevented 100 by virtue of the lock connection between the same and the table as effected by the rolls 28.

Although I have shown and described one embodiment of my invention it is to be understood that I am not to be limited to 105 the specific structure herein described and claimed nor to the particular arrangement of the parts since it will be manifest that various changes will be made in the scope of the appended claim without departing 110.

from the spirit or sacrificing any of the advantages of the invention.

What I claim as new is:

The combination of a headlight having 5 openings in its base, a fixed table support having guide openings, a rotatable disk let into the upper face of the table and having pins arranged in the base openings of the headlight, a locking connection between the 10 table and headlight including tapered rolls

arranged in the guide openings of the table and connected to the headlight, and means for turning the disk in opposite directions.

In testimony whereof I affix my signature in presence of two witnesses.

ALONZO S. WILLIAMS.
